POCKET

Filed March 4, 1922

Fig. 1.

UNITED STATES PATENT OFFICE.

WILLIAM J. STOTT, OF WORCESTER, MASSACHUSETTS.

POCKET.

Application filed March 4, 1922. Serial No. 541,133.

To all whom it may concern:

Be it known that I, WILLIAM J. STOTT, a citizen of the United States, residing at Worcester, in the county of Worcester and 5 State of Massachusetts, have invented a new and useful Pocket, of which the following is a specification.

The principal objects of this invention are to provide a pocket as an article of manufacture which can be sold in the stores in its completed condition and will be suitable for ready attachment to the inside of a similar pocket so as to constitute a reinforcement or eventually a replacement 15 thereof; also to provide an improved fastening means which can be applied in such a way that when sold on the market it will be already in position on the pocket and can be attached without difficulty to the inside of 20 the pocket for which it is intended.

Further objects and advantages of the invention will appear hereinafter.

Reference is to be had to the accompanying drawings, in which—

25 Fig. 1 is a view of a pair of trousers showing the application thereto of a pocket constructed in accordance with the present invention;

Fig. 2 is a view of the end of this pocket 30 showing it as it is intended to be sold on the market but with parts broken away to show the interior;

Fig. 3 is a detail view of one of the attaching elements, showing it ready to be applied to a worn out pocket;

Fig. 4 is a sectional view showing it after 35 it is applied and secured, and

Fig. 5 is a perspective view of one of the attaching devices removed from the pocket.

40 This invention is designed particularly for application to pockets of trousers, overalls and other garments that are used frequently, as for example, pockets that are used for carrying coins, keys and other 45 metallic articles. Such pockets wear out easily and even if mended in the ordinary way they wear through again very quickly.

I propose to provide a complete pocket 50 instead of a patch or an ordinary method of mending. This pocket is so arranged that it can be supplied to the trade with its fastening devices upon it and sold as a separate article of manufacture. It is then merely placed in the pocket which is worn 55 or torn and the fastening devices attached.

It is not a detachable device, for after it is once attached it is not intended that it should be removed again and is not provided with any convenient means for removing it, although it can be removed if necessary. 60

I have shown the invention as in the form of a pocket for application to the side pockets of trousers or the like, but, of course, it is to be understood that it is not limited to that particular use as it can be applied to 65 vertical pockets having horizontal tops. In this form the pocket which is the subject of this invention comprises a bag having a depending portion and extending upwardly on a curve so that its hand opening is in the 70 side and vertical instead of horizontal as it would be if applied to an ordinary vertical pocket.

The edges at this opening is finished in any desired way common in the clothing industry. This involves the turning over of the edge and hemming it to provide a double thickness having a smooth and neat appearance. This hemming is done by running 75 a row of stitching 10 along to connect the two thicknesses of cloth which constitute the hem. At a point as near as possible to the finished outer edge of the opening I also provide two parallel rows of stitches 11 and 12 located quite close together. They also connect the two thicknesses of cloth and between them there is a space on the outside

extending all the way around the hand opening of the pocket. In this space I place the backs 13 of the fastening devices. These 80 fastening devices are in the form of two-pointed pins or staples. They are formed 85 of round wire and their ends are pointed so that they can be forced through the cloth. Their backs 13 are flattened for helping hold 90 them in position. To prepare this device to put on the market they are inserted at intervals in the space between the stitches 11 and 12 with their points projecting parallel to each other in the plane of the cloth 95 but on the outside. This is done by making them of soft brass wire and originally 100 straight. They are inserted in the space far enough so that the backs 13 are covered by the cloth and then the two points are 105 bent at right angles as indicated in the figures. This furnishes a pocket which has the fastening devices extending all around it on the outside and projecting from it in its own plane so that it can be sold on the 110

market in this condition ready for application. I also prefer to sew a piece of tape 14 on the inside of the opening all around to further protect the backs of the fastening devices.

It will be noted that, as located in Figs. 1 and 2, the staples or fastening devices are so placed that the flat backs 13 are transverse to the plane of the pocket. This is merely for convenience in handling and selling the goods. When the pocket is to be used each of these fastening devices is turned around to a point at right angles to its original position so that its flattened surface comes parallel to the plane of the pocket as shown in Fig. 3. Then the two prongs or points are forced through the pocket 20 which is the pocket located in the garment and the one that is to be reinforced. They are not, however, forced through the outer fabric 21 which is the fabric of the trousers or other garment but they are bent in under it as shown in Fig. 4. In this way the pocket is fastened all the way around near its edge and the sharp points are concealed and located where they will not injure the wearer or his clothing.

This provides an inner pocket which is as good as the original one was when new and perhaps better. It is firmly fixed in position without the use of any special tools or implements and a man who is unfamiliar with sewing can apply it accurately and neatly. It is not expected that this inner pocket will have to be replaced but if it is, another one can be applied to it in the same way that this one was applied or the first one attached can be removed by bending

back the ends of the fastening pins, taking them out with the pocket.

Although I have illustrated and described only a single form of the invention, I am aware of the fact that modifications can be made therein by any person skilled in the art without departing from the scope of the invention as expressed in the claims. Therefore, I do not wish to be limited to all the details of construction herein shown and described, but what I do claim is:—

1. As an article of manufacture, an attachable pocket having a hand opening and provided with a continuous row of fastening devices pivotally secured thereto projecting outwardly and extending around said opening, said fastening devices having points capable of lying in the plane of the pocket and of being swung to a plane transverse thereto and adapted to be forced outwardly through the fabric of a pocket to which this article is to be attached and to be bent down on the outer surface thereof to secure this article on the inside thereof.

2. As an article of manufacture, a pocket for repair purposes having a hemmed hand opening and provided with two rows of stitches extending all the way around said opening and spaced a short distance apart for securing together the inner and outer fabric constituting the hem around said opening, and staple-shaped fastening pins having their backs located in said space between said rows of stitches so that they can turn about their backs as pivots.

In testimony whereof I have hereunto affixed my signature.

WILLIAM J. STOTT.
